US00D931846S

(12) **United States Design Patent** (10) **Patent No.:** **US D931,846 S**
Lee (45) **Date of Patent:** ** *Sep. 28, 2021

(54) **CASE FOR ELECTRONIC COMMUNICATIONS DEVICE**(71) Applicant: **SPIGEN KOREA CO., LTD.**, Seoul (KR)(72) Inventor: **Jong Hwa Lee**, Seoul (KR)(73) Assignee: **SPIGEN KOREA CO., LTD.**, Seoul (KR)

(*) Notice: This patent is subject to a terminal disclaimer.

(**) Term: **15 Years**(21) Appl. No.: **29/724,115**(22) Filed: **Feb. 12, 2020****Related U.S. Application Data**

(63) Continuation of application No. 29/681,409, filed on Feb. 25, 2019, now Pat. No. Des. 877,136.

(51) **LOC (13) Cl.** ..... **14-03**(52) **U.S. Cl.**USPC ..... **D14/250**(58) **Field of Classification Search**

CLAIM

The ornamental design for a case for electronic communications device, as shown and described.

DESCRIPTION

FIG. 1 is a front perspective view of a case for electronic communications device in an open position showing my new design;

FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is a front perspective view thereof in a closed position, shown in an environment of use;
FIG. 10 is a rear perspective view thereof in a closed position, shown in an environment of use;
FIG. 11 is a front perspective view thereof in an open position, shown in an environment of use;
FIG. 12 is a rear perspective view thereof in an open position, shown in an environment of use; and,
FIG. 13 is an enlarged detail view of the encircled region of FIG. 1.

The dot-dash broken line circle in FIGS. 1 and 13 delineates a portion of the case that is part of the claimed design and that is shown on an enlarged scale in FIG. 13. The dashed broken lines depict an environmental foldable electronic communications device and portions of the case that form no part of the claimed design.

The broken lines depict environmental subject matter and portions of the case for electronic communication device that form no part of the claimed design.
